UNITED STATES PATENT OFFICE.

JOHN J. O'CONNOR AND RALPH M. WHITE, OF WELLSVILLE, NEW YORK,
ASSIGNORS OF ONE-THIRD TO CHARLES L. GISH, OF SAME PLACE.

CAR-COUPING.

SPECIFICATION forming part of Letters Patent No. 271,106, dated January 23, 1883.

Application filed November 9, 1882. (No model.)

To all whom it may concern:

Be it known that we, JOHN J. O'CONNOR and RALPH M. WHITE, of Wellsville, in the county of Allegany and State of New York, 5 have invented a new and Improved Car-Coupling, of which the following is a full, clear, and exact description.

The object of our invention is to provide simple and efficient couplings especially adapted 10 for freight-cars, which can be readily applied in place of the ordinary draw-heads without requiring alterations in the cars, and also that can be used with the ordinary draw-head, and, further, to construct such couplings so that 15 they may be operated from the top of the car or at the side of the car.

To these ends our invention consists in 20 hooked coupling-bars, constructed and arranged for operation as hereinafter described and claimed.

Reference is to be had to the accompanying drawings, forming part of this specification, in which similar letters of reference indicate corresponding parts in both the figures.

25 Figure 1 is a side elevation, partly sectional, showing our coupling devices as applied to the cars. Fig. 2 is an inverted plan view of the cars and couplings.

The coupling-hooks or draw-bars are placed 30 upon the cars A A in place of the usual draw heads and bars.

B B are the draw-bars, formed with double hooks a at their outer ends, of spear-head form, the taper or bevel of the heads being up- 35 on the upper and under side, so that when two cars are brought together the hooks shall pass one above the other and engage by their shoulders. The draw-bars B are formed at their rear ends with shanks or spindles b, that

40 extend through slots in plates c c, that are sustained transversely of the car by brackets d d, attached to the bottom of the car. These plates c are loose, and on the stem b, between these plates, are spiral springs, e, which serve 45 as buffers and draw-springs. The forward ends of the draw-bars B are supported by brackets f, and at one side of the draw-bars is attached a spring, g, which tends to retain the bars in a central position horizontally, and

50 there are also upon the upper side of the draw-

bars springs h, which act to press the bars downward and retain the hooks in engagement.

Upon the ends of the cars are fitted vertical rods i, formed with cranks at their lower ends, 55 and connected by rods k to the draw-bars B; and the rods i are provided with handles l l, by which they may be turned, and the draw-bars thus moved sidewise out of position for engagement with each other. One handle on 60 the rod is placed at the upper end for operation by a brakeman at the top of the car, while the other is placed at a convenient height for operation at the bottom of the car.

Upon one end of each draw-bar B is fitted 65 by a brace, o, a socket, m, of a form for receiving an ordinary link, and through this socket is an aperture for receiving the coupling-pin. When the draw-bar is drawn at one side and locked by means of the hook n or 70 other device the socket m is brought in position for receiving a link from an opposite car. This allows the couplings to be used with cars having draw-heads of ordinary form.

These coupling devices allow for considerable variation in the height of the cars. They 75 can be applied to a car after the ordinary draw-bar is removed, and being of simple and durable construction there is no liability of their getting out of order.

Having thus described my invention, what I 80 claim as new, and desire to secure by Letters Patent, is—

1. In a car-coupling, the combination, with the draw-bar B, of the socket m, extending 85 from one side of said bar, said draw-bar being adapted to be swung laterally to bring the socket m in line with the coupling-link of the approaching car, as set forth.

2. In a car-coupling, the combination, with 90 the spring draw-bar B, of the laterally-projecting socket m and the means for holding the draw-bar out of action and the socket m in line with the coupling-link of the approaching car, as set forth.

JOHN J. O'CONNOR.
RALPH M. WHITE.
